Specification for Design.

Patented Dec. 24, 1918.

Application filed February 15, 1918. Serial No. 217,428. Term of patent 3½ years.

To all whom it may concern:

Be it known that I, WILLIAM BUSH, a citizen of the United States, residing at Worcester, in the county of Worcester and State of Massachusetts, have invented a new, original, and ornamental Design for a Child's Car, of which the following is a specification, reference being had to the accompanying drawing, forming part thereof, in which—

The figure is a perspective view of a child's car illustrating my new design.

I claim:—

The ornamental design for a child's car, as shown.

WILLIAM BUSH.
